[57] **CLAIM**

The ornamental design for a support rack for a flat saddle or the like, as shown and described.

DESCRIPTION

FIG. 1 is a perspective view taken from the top, front, and right side of the support rack for a flat saddle or the like showing my new design.

FIG. 2 is a top plan view thereof.

FIG. 3 is a left side elevational view thereof.

FIG. 4 is a front elevational view thereof.
The broken line representation of a support stand shown in FIG. 1 is for purposes of illustration and forms no part of the claimed design.

FIG. 1

FIG. 2

FIG. 3

FIG. 4
